UNITED STATES PATENT OFFICE.

JAMES WILLIAM BOOTH, OF BARNSDALL, OKLAHOMA.

STILL CLEANER.

Application filed February 26, 1924. Serial No. 695,315.

The present invention relates an apparatus for cleaning high pressure stills.

At the present time, when cleaning high pressure stills, it is necessary to shut down the still and permit it to cool before commencing the manual or mechanical cleaning of the still to remove deposits of carbon, tar, or coke from the sides and bottom of the still, causing great delay and loss of time. If the still is not perfectly clean so-called "hot spots" will form resulting in the rupture of the still.

The present apparatus will eliminate these disadvantages and the still need not be shut down as the cleaning is continuous. The drawing off of the heavy precipitates from the bottom accordingly must take place from time to time as this apparatus will remove the tar from the sides of the still, and this tar, being heavier than the oil, will naturally gravitate to the bottom of the still, there to be drawn off.

Ordinarily, carbon is deposited on the sides of the still in the form of a tar-like substance, and by latent heat, this substance is baked to a coke which is very difficult to remove. Where my present apparatus is used there will be no time for the coke to form as the deposits are constantly dislodged from the still walls.

In the accompanying drawings, one embodiment of the invention is illustrated, and—

Figure 1 is a fragmentary vertical section of a still with the cleaner in position;

Figure 2 is a horizontal section along line 2—2 of Figure 1;

Figure 3 is a vertical section of the operating gears for the cleaner;

Figure 4 is a fragmentary horizontal section along line 4—4 of Fig. 3;

Figure 5 is a fragmentary side elevation of the clutches for the operating gears;

Figure 6 is a fragmentary vertical section along line 6—6 of Figure 2;

Figure 7 is a horizontal section along line 7—7 of Figure 6;

Figure 8 is a horizontal section along line 8—8 of Figure 1;

Figure 9 is a side elevation showing a modified form of a scraper; and

Figure 10 is a perspective view of one of the details of the timing device.

In the drawings, reference numeral 15 represents a cylindrical still for hydrocarbons. In the drawings, the still is represented as being erected with its axis vertically positioned but it is evident that the apparatus may equally well be applied to a horizontally positioned still. The upper end of the still has a neck 16 closed by a cover 17 forming a dome 45 on the still. Similarly the bottom 18, which is preferably semi-spherical, has a central annular downward extension 19 which is closed by a cover 20. In this manner a receptacle 21 for the heavy precipitates is formed at the bottom of the still, and the center of the cover 20 is provided with a suitably valved drain pipe 22. The top and bottom covers 17 and 20 are firmly secured in position by bolts or the like.

Reference numeral 23 represents a drive shaft which is revolvably mounted in a bushing 24 at the lower end thereof, see Fig. 6. This bushing is keyed, as at 24', or in any other manner rigidly secured in a chair 25. This chair fits in the annular extension 19 and is provided with flanges engaging between the flanges of said extension and the cover 20 so as to be firmly held in position. On the bushing 24 is loosely mounted a gear wheel 26 in mesh with a pinion 27 keyed on a feed shaft 28.

A latch-dog 29 is pivoted, as at 30, on the gear wheel 26, see Figs. 6 and 7, and the bushing 24 is provided at one side with a notch 31 in which the latch-dog 29 is adapted to engage. It is evident that when so engaged the latch-dog will firmly lock the gear wheel 26 to the bushing 24 and as the latter is keyed in the chair 25, the gear wheel 26 will, accordingly, be stationary during such engagement, or, in other words, the pinion 27 on the feed shaft 28 will rotate with relation to the gear wheel 26.

A short distance above the bushing 24, there is keyed to the shaft 23 a bracket 32 in which the feed shaft 28 is revolvably

mounted. At the outer end of this bracket is firmly secured by bolts 33 a scraper 34 having the contour of the semi-spherical bottom 18. As the drive shaft 23 turns it 5 will communicate a rotary motion to the scraper 34 through the intermediary of the bracket 32 which is keyed and pinned fast to the shaft 23 as already described. Accordingly, the scraper will always participate 10 in the rotation of the drive shaft 23 so that any heavy substances that may collect on the bottom 18 will be continuously stirred by the scraper and gradually carried down into the receptacle 21 from which they may 15 subsequently be drained through the drain pipe 22.

As the scraper and the bracket 32 revolve around the axis of the drive shaft 23, the feed shaft 28 will receive a planetary motion 20 around the same axis and as the pinion 27 is of a different, preferably smaller, diameter than the gear wheel 26, the feed shaft 28 will be given a different speed of rotation to that of the drive shaft 23. The upper end of the 25 feed shaft 28 is revolvably mounted in a bracket 35 which is rigidly secured on the drive shaft 23.

The feed shaft 28 is threaded between the bracket 32 and the bracket 35 and engages 30 in a carriage 36 which is correspondingly threaded. This carriage has a sliding but non-revovable connection with the drive shaft, or, in other words, the carriage is keyed on said shaft to slide up and down between 35 the bracket 32 and the bracket 35, actuated by the feed shaft 28.

On the carriage 36 are secured a number 40 of radial arms 37, four being shown in the drawings. On each arm is mounted a side scraper or brush 38. The inner end of this brush contacts with the short arm of an elbow lever 39, on the long arm of which is secured a weight 40 preferably in such a manner that it may be adjusted in and out 45 on the elbow lever. This arrangement compels the brush 38 to constantly press with its bristles 41 against the cylindrical side of the still.

In the carriage 36 is secured a downwardly directed finger 42 which is adapted to engage 50 with an arm 82 on the latch dog 29 when the carriage and brushes have descended to the bottom of the still and to disengage the latch-dog from the notch 31 in the bushing 24, thereby permitting free rotation 55 of the gear wheel 26 around the axis of the drive shaft 23 for a purpose that will be described later. A stop 83 is provided on the gear wheel for limiting the swing of the dog.

In Fig. 9 is shown a modified form of a side scraper for the still which, instead of a bristle brush 38, has a comb 43 with teeth 44 adapted to contact with the inner side of the still. The comb is carried on a slide 96 60 guided upon the arm 37 and pressed out-

wardly in radial direction by means of a spring 46. It is evident that the scrapers 38 and 43 may be furnished on alternate arms in the same still or that all the arms may be provided with only one kind of scraper, as 70 found most suitable for the particular still.

The upper end of the drive shaft 23, which is preferably hollow, extends into the dome 45 and this end of the shaft is provided with a socket 84 fitting closely the square end 47 75 of an extension shaft 48 in axial alinement with the drive shaft 23. The extension shaft is mounted to revolve in the top cover 17 and a bearing plate 49 at the upper end thereof. The cover is preferably constructed as a 80 housing for the driving gears and the timing device and has for this reason an upwardly extended cylindrical wall 50 at the upper end of which are provided ears 51 upon which the bearing plate 49 rests and is 85 held in position by means of bolts 52. At the bottom of the housing is furnished an annular ledge 53 upon which a lower bearing plate 54 is deposited and kept in position by studs 55 secured in the ledge 53. The housing 90 50 including the top cover 17 is preferably a cast steel cylinder and on one side thereof is furnished a stuffing-box 56 for a motor driven main shaft 57. At the inner end of the main shaft 57 is secured a bevel 95 pinion 58 which meshes with the bevel gear 59 secured on an intermediary shaft 60 revolvably mounted in the top and bottom bearing plates 49 and 54. Integral with the bevel gear 59 is shown a spur gear 61 in mesh with 100 a corresponding gear 62 loosely mounted on the extension shaft 48. Similarly a second spur gear 63 is keyed to the intermediary shaft 60 at the lower end thereof and meshes with an idler 64 mounted to revolve on the 105 stub shaft 65 carried upon the bearing plate 54. This idler 64 in turn meshes with a spur gear 66 loosely mounted on the extension shaft 48 as best shown in Fig. 3. The gears 61, 62, 63, 64 and 66 are preferably so selected that the ratio of revolution between 110 shafts 60 and 48 is as one to one.

Between the spur gears 62 and 66 are inserted clutches 67 and 68 slidably but non-revovably mounted on the extension shaft 48. 115 Each of these clutches has teeth 69 and 70 respectively, which are preferably tapered or pointed in order to facilitate quick and easy engagement with corresponding teeth in the gear wheels 62 and 66. Each clutch has an axially slidable sleeve 71 between which and its clutch is inserted a compression spring 72 tending to force the sleeve and clutch apart. Each sleeve has an annular groove 73.

A slide 75 is mounted on a rod 76, the 125 axis of which is parallel to the axis of the drive and extension shafts 23 and 48, the rod being suitably supported between the top and bottom bearing plates 49 and 54. This slide 75 has rigid fingers 77 adapted to 130

respectively engage in the annular grooves 73 of the clutch sleeves 71 in order to hold them a permanent distance apart. On the side of the slide opposite to that carrying the fingers 77 is a projecting stud 78, and this stud has preferably a roller 79 which engages in a cam groove 80, see Fig. 10, in a cam disk 81. The cam groove 80 is positioned eccentrically on the disk in order to 10 actuate the sleeves 71 and effect engagement of the upper clutch 67 with the teeth of the spur gear 62 when the slide 75 stands at the upper end of its stroke and effect engagement of the clutch 68 with the gear 66 15 when the slide 75 is at the other end of its stroke.

The timing device consists of a train of gears actuated from the main shaft 57 through the spur gear 66. A pinion 85 is 20 revolvably mounted on the extension shaft 48 below and keyed to the spur gear 66 so as to constantly revolve at the same speed at the latter. An idler 86 journaled on the bottom bearing plate 54 meshes with this 25 pinion 85 as well as with a second pinion 87 secured on a worm spindle 88 mounted to revolve in bearings provided in the top and bottom plates 49 and 54. The worm 89 of this spindle engages with the worm wheel 90 keyed on a stub shaft 91 mounted horizontally in suitable bearings 92. The inner end of said stub shaft has secured thereon a pinion 93 meshing with a spur gear 94 secured on the same horizontal shaft 95 as 30 the cam disk 81. The speed ratio of this train of gears has been so selected that the cam disk 81 makes one revolution while the cleaning brushes complete their cycle from top to bottom of the still and back again 35 or, in other words, the slide 75 completes a double stroke from top to bottom and return.

The clutch springs 72 are comparatively 40 strong and permit only a short extension and their outer ends are secured to their respective clutches 67 and 68 so that, for instance, the lower clutch 68, as illustrated 45 in Fig. 3, is suspended by the spring from its sleeve 71 without engaging the teeth of the bottom clutch. However, if the clutch 50 were permitted to descend freely at the same ratio as the slide 75, it is evident that the teeth 70 would soon begin to engage the corresponding teeth in the bottom spur gear 66 and possibly before the teeth of the top 55 clutch 67 had disengaged from the teeth of the upper spur gear 62. This would cause an interruption of the proper operation of the mechanism and a special retarding device is for this purpose furnished for the 60 clutches.

The retarding device, best illustrated in Fig. 5, consists of a double armed lever 100, fulcrumed, as at 101, upon the side of the yoke 121. The yoke 121 spans the head 75

and is secured at either end or both ends to the rod 76 at points beyond the limits of movement of the slide so that it will not interfere with said movement, and, to economize space, the slide may be grooved in one side to accommodate the body of the yoke, as shown in Fig. 4. At each end of the lever 100 is journaled, as at 102, a rocking arm 103 having a limited swinging motion on its journal. Each rocking arm 103 extends in the direction of the corresponding one of the clutches 67 and 68 and has a small friction roller 104 on its inner end adapted to engage an annular collar 105 on the clutch when the lever 100 is tilted in one direction. This tilting is accomplished by means of a raised cam 106 on the cam disk 81 engaging with a second roller 107 at the outer end of the rocking arm 103. The raised cam 106 is substantially of semi-circular extent 85 so that when the roller 107 of one of the rocking arms 103 engages the top surface of the cam 106, the corresponding roller 107 on the other rocking arm rolls along the face of the cam disk 81. The height of the cam with relation to this face of the disk is such that the roller 104 of the upper rocking arm 103, for instance, as seen in Fig. 5, will be interposed in the path of the clutch collar 105 when the roller 107 of said arm rests upon the raised cam 106, while the roller 104 on the other rocking arm is simultaneously retracted out of the path of the collar 105 of the lower clutch 68. The slopes 120 at the ends of the raised cam 106 90 are positioned substantially diametrically opposite each other so that the swinging of the lever 100 is almost instantaneous.

By this arrangement it is possible for the slide 75 and the sleeves 71 to travel unobstructed while the clutches will be intercepted by the respective rocking arms 103 and retained until the end of the stroke upward or downward of the side cleaners, whereupon the rocking arm will instantaneously release its corresponding clutch which, when actuated by its spring 72, will quickly engage with the corresponding spur gear 62 or 66.

At 110 and 111 are shown inlet and outlet oil ports to the housing for keeping the gears well lubricated. In order that this cold oil may not escape into the still a bushing 112 is provided in the cover 17 around the extension shaft 48. It will naturally not do to permit cold oil from the housing to drain into the still when in operation and this bushing only permits sufficient oil to pass down the shaft to properly lubricate the same, the quantity, however, being so small that it will have no effect upon distillation of the oil in the still.

As the extension shaft 48 is slidably connected by means of its square end 47 with the socket 84 of the drive shaft 23 it will 130

be possible to remove the entire housing, with the gears it contains, from the top of the still without disturbing the scrapers. It may also be possible to leave the housing 5 and cover 17 in position and to remove the gears, mounted in the top and bottom bearing plates 49 and 54, assembled. In both cases the extension shaft 48 will be withdrawn from engagement with the socket 84 of the drive shaft 23 without the necessity of any special coupling. Another advantage of connecting the extension shaft with the drive shaft 23 in the manner described 10 and shown, is that considerable expansion 15 will be permitted at the joint.

The only difference between the apparatus for a vertical and a horizontal still is that the drive shaft will continue through the heads of the still and that the drive 20 shaft 23 and the feed shaft 28 have to be supported medially in the still with two arms, the scrapers traveling from end to center and reverse.

It has been found difficult to regulate the 25 timing device for reversing the travel of the side scrapers because if they travel a small fraction in one direction beyond the desired turning point this discrepancy will gradually multiply so that the machinery 30 will ultimately jam at top or bottom. A device has, accordingly, been introduced in this timing gear permitting a greater number of revolutions in going down than in going up. In other words, the feed shaft 35 28 is stopped at a certain point so that the extra revolutions will cause no travel up or down of the scrapers, but they will continue to rotate in the same horizontal plane. The latch-dog 29 and operating finger 42 40 furnish the engaging and disengaging means of the feed shaft 28.

As the mechanism is completely enclosed in the still and in the housing it is impossible to observe whether it is functioning satisfactorily or not. A recording meter 45 is therefore provided which has electrical connection with a contact plug 115, see Figs. 1 and 8, mounted in suitable insulations 116 in the wall of the still. Any number of 50 these contact plugs may be provided but there should at least be one near the top of the still and another near the bottom thereof, this is indicated in Fig. 1 of the drawings. These two contact plugs are then 55 arranged so that when the scraper brushes 38 are at the end of travel in upward or downward direction these brushes will sweep over the contact plug 115 thus completing the electric circuit so that a record on the 60 meter will be given at the reversing points of the scrapers.

The operation of the device is as follows:

Supposing that the different parts of the apparatus are in their relative positions as 65 indicated in Figs. 1, 3 and 5, that is to

say, the side scrapers have arrived at the bottom of the still and are ready to turn; supposing, further, that the main shaft 57 is revolving thereby actuating the spur gears 62 and 66 which are thus revolving 70

at the same speed but in opposite directions they being loosely mounted on the extension shaft 48; the friction roller 104 of the upper rocking arm 103 is now in engagement with the annular collar 105 of the upper 75

clutch 67, thereby compressing the spring 72 against the sleeve 71, which is shown at the upper end of its stroke, by the slide 75. The teeth of both the top and bottom 80

clutches are out of engagement with the teeth of the corresponding spur gears and the shafts 23 and 48 are, accordingly, momentarily stationary. As the timing device, however, is continuously rotated by the lower spur gear 66 through the pinion 85, 85

the cam disk 81 continues to turn. At the next fraction of a turn the friction roller 107 of the upper rocking arm 103 will slip down from the cam 106 to the face of the cam disk 81 while the corresponding roller 90

on the lower rocking arm 103 will ride up on the cam 106. In this manner the lever 100 is swung on its fulcrum 101 thereby disengaging the friction roller 104 on the upper rocking arm 103 from the annular 95

collar on the upper clutch 67, while the lower roller 104 is then thrust into the path of the annular collar 105 on the lower clutch 68. Directly the clutch 67 is released by 100

the rocking arm 103 it is shot upward by its spring 72 so that its teeth 69 become practically instantaneously engaged with the clutch teeth on the upper spur gear 62. The clutch 67 being keyed to the extension 105

shaft 48 now communicates the rotation of the spur gear 62 to said shaft and through the same to the drive shaft 23. The arm 37 with the side scraper 38 will now start to revolve and, as the gear wheel 26 is locked to the chair 25 by the latch-dog 29 110

and the bushing 24, the planetary motion of the bracket 32 will cause the pinion 27 to roll on the gear 26 and turn the feed shaft 28 in its bearing bracket 32. As, however, this feed shaft is threaded in the carriage 36 it will cause this carriage together 115

with arms 37 to travel upwardly on the drive shaft 23. Accordingly, the scrapers will follow a helical path around the side wall of the still. The bearing bracket 32 carries 120

the bottom scraper 34 which consequently describes a circular motion around the axis of the drive shaft 23 without leaving the bottom 18 of the still so that, while the carriage 36 and the arms 37 are ascending, 125

the distance between the same and the bottom scraper 34 gradually increases. The distance between the same and the bottom scraper 34 gradually increases.

From the above given description it will now be understood how the upper clutch 67 becomes disengaged from the spur gear 62 130

- when the scrapers have arrived at the upper end of their travel and how the lower clutch engages with the lower spur gear 66 upon its release by the lower rocking arm 103. It should here be noted that the cam groove 80 is set slightly ahead of the reversing action of the clutches. That is to say, the slide 75 arrives at the top end of its stroke before the side scrapers are reversed, so that, for instance, the upper clutch will start on its way down before the side scrapers reach the turning point and the clutch teeth will have had time to disengage at the right moment.
- 15 As has already been stated, the shafts 23 and 48, together with the scrapers are permitted to make one or more idle turns before the scraper is permitted to again ascend after reaching the bottom of the still. This is accomplished by the operating finger 42 during its last descending turn to engage the arm 82 of the latch-dog 29. The latter is then instantly lifted out of the notch 31 in the bushing 24 so that the gear wheel 26 25 is free to rotate on the bushing. The wheel 26 is thus carried around with the bracket 32 and the feed shaft 28 and as no rolling motion then takes place between the pinion 27 and the gear wheel 26, the feed shaft 28 30 stops turning around its own axis. The distance between the carriage 36 with the scraper arms 37 and the bottom 18 of the still remains constant for a short while. As soon, however, as the upper clutch again engages with the top spur gear 62 and shafts 23 and 48 begin to revolve in the opposite direction, the operating finger 42 will strike the back of the arm 82 on the latch-dog 29 and force the same to engage in the notch 31 of the bushing 24. As the gear wheel 26 40 then becomes locked to the chair 25 the pinion 27 will be compelled to roll on the spur gear 26 thus rotating the feed shaft 28 around its own axis. The carriage 36 together with the arms 37 on the side scrapers 45 will, accordingly, begin to ascend.
- Having thus described the invention, what is claimed as new is:
1. Cleaning mechanism for stills comprising, in combination, a drive shaft rotatably mounted in the still, a carriage slidably mounted on said shaft and rotatable therewith, cleaning elements on said carriage to contact with the wall of the still, means for automatically alternately rotating said shaft first in one direction and then in the opposite direction, and means operating in consonance with the rotation of the shaft to automatically move the carriage longitudinally of the shaft.
- 50 2. Cleaning mechanism for stills comprising, in combination, a drive shaft rotatably mounted in the still, a carriage slidably mounted on said shaft and rotatable therewith, cleaning elements on said carriage to contact with the wall of the still, means for automatically alternately rotating said shaft first in one direction and then in the opposite direction, and means operating in consonance with the rotation of the shaft to automatically move the carriage longitudinally of the shaft.
- 55 3. Cleaning mechanism for stills comprising, in combination, a drive shaft rotatably mounted in the still, a carriage slidably mounted on said shaft and rotatable therewith, cleaning elements on said carriage to contact with the wall of the still, means for automatically alternately rotating said shaft first in one direction and then in the opposite direction, and means operating in consonance with the rotation of the shaft to automatically move the carriage longitudinally of the shaft, said means including a feed shaft having threaded engagement with the carriage, means on the drive shaft for supporting said feed shaft, a stationary gear, and a pinion on said feed shaft meshing with said gear.
- 60 4. Cleaning mechanism for stills comprising, in combination, a drive shaft rotatably mounted in the still, a carriage slidably mounted on said shaft and rotatable therewith, cleaning elements on said carriage to contact with the wall of the still, means for alternately rotating said shaft first in one direction and then in the opposite direction, and means for moving said carriage longitudinally of the shaft, said means including a feed shaft having threaded engagement with the carriage, means on the said drive shaft supporting said feed shaft, a gear, a latch normally locking said gear in fixed position, a pinion on said feed shaft meshing with said gear, and a releasing element on said carriage for coaction with the latch to move the same to inactive position to permit free rotation of said gear.
- 65 5. Cleaning mechanism for stills comprising, in combination, a drive shaft rotatably mounted in the still, a carriage slidably mounted on said shaft and rotatable therewith, cleaning elements arranged on said carriage to contact with the wall of the still, means for alternately rotating said shaft first in one direction and then in the opposite direction, and means for moving said carriage longitudinally of the shaft in opposite directions and in consonance with the alternate opposite rotation of the shaft, the said means including a feed shaft having threaded engagement with the carriage, means on said drive shaft for supporting said feed shaft, a fixed bearing for one end of the drive shaft, a gear rotatably engaged with the bearing, a latch upon the gear for coaction with the bearing to render the said gear stationary with respect to the bearing, a pinion on the feed shaft meshing with the said gear, and a finger upon the carriage for coaction with the said latch when the carriage is rotating and has reached substantially the limit of its movement in the direction of the said gear to move the latch to inactive position and permit free rotation of said gear.
- 70 6. Cleaning mechanism for stills comprising, in combination, a drive shaft rotatably mounted in the still, a carriage slidably mounted on said shaft and rotatable therewith, cleaning elements on said carriage to contact with the wall of the still, means for

- alternately rotating said shaft first in one direction and then in the opposite direction, and means for moving said carriage longitudinally of the shaft in opposite directions 5 in consonance with the rotation of the shaft in opposite directions, said shaft rotating means including gears freely rotatable upon the drive shaft, means for rotating said gears in opposite directions, a clutch for co-action with each of said gears slidably mounted upon the said drive shaft, and means operating automatically to synchronously operate said clutches and alternately effect their coaction with the respective 10 gears at the end of each longitudinal travel of said carriage.
6. Cleaning mechanism for stills comprising, in combination, a drive shaft rotatably mounted in the still, a carriage slidably mounted on said shaft and rotatable therewith, cleaning elements upon the carriage to contact with the wall of the still, means for alternately rotating said shaft first in one direction and then in the opposite direction, and means for moving said carriage longitudinally of the shaft alternately in opposite directions in consonance with rotation of the shaft in opposite directions, said shaft-rotating means including gears mounted upon the drive shaft for rotation with respect thereto, means for rotating said gears in opposite directions, a clutch for co-action with each of said gears slidably mounted upon said drive shaft, and means 20 operating automatically to synchronously actuate said clutches and alternately effect their coaction with the respective gears at the termination of each longitudinal travel of the carriage, said last mentioned means including a member mounted for reciprocation with respect to the shaft, a sleeve slidably connected with each clutch, a spring tending to separate each clutch and its respective sleeve, the said member engaging both of said sleeves whereby to effect their movement in unison, a rotatable disc, and means for rotating the same, the said disc having means coacting with said member to reciprocate the same.
8. Cleaning mechanism for stills comprising, in combination, a shaft rotatably mounted in the still, a carriage slidably mounted on said shaft and rotatable therewith, cleaning elements upon said carriage to contact with the wall of the still, means for alternately rotating said shaft first in one direction and then in the opposite direction, and means for moving said carriage longitudinally of the shaft alternately in opposite directions in consonance with rotation of the shaft in opposite directions, said shaft-rotating means including gears mounted upon the drive shaft for rotation with respect thereto, means for rotating said gears in opposite directions, a clutch for co-action with each of said gears slidably mounted upon said drive shaft, and means 30 operating automatically to synchronously actuate said clutches and alternately effect their coaction with the respective gears at the termination of each longitudinal travel of the carriage, said last mentioned means including a member mounted for reciprocation with respect to the shaft, a sleeve slidably connected with each clutch, a spring tending to separate each clutch and its respective sleeve, the said member engaging both of said sleeves whereby to effect their movement in unison, a rotatable disc, and means for rotating the same, the said disc having means coacting with said member to reciprocate the same.
7. Cleaning mechanism for stills comprising, in combination, a shaft rotatably mounted in the still, a carriage slidably mounted on said shaft and rotatable therewith, cleaning elements upon said carriage to contact with the wall of the still, means for alternately rotating said shaft first in one direction and then in the opposite direction, and means for moving said carriage longitudinally of the shaft alternately in opposite directions in consonance with rotation of the shaft in opposite directions, said shaft-rotating means including gears mounted upon the drive shaft for rotation with respect thereto, means for rotating said gears in opposite directions, a clutch for coaction with each of said gears slidably mounted upon said drive shaft, and means operating automatically to synchronously actuate said clutches and alternately effect their coaction with the respective gears at the termination of each longitudinal travel of the carriage, said last mentioned means including a member mounted for reciprocation with respect to the shaft, a sleeve slidably connected with each clutch, a spring tending to separate each clutch and its respective sleeve, the said member engaging both of said sleeves whereby to effect their movement in unison, a rotatable disc, means for rotating the same, the said disc having means coacting with said member to reciprocate the same, a centrally fulcrumed lever upon the said member, a finger projecting from each end of the lever in the direction of a respective one of the clutches, a cam upon said disc coacting with the fingers to effect rocking of the lever and corresponding movement of the fingers whereby to interpose one of said fingers in the path of the respective clutch and simultaneously retract the other finger to position it out of the path of the respective clutch.
9. Cleaning mechanism for stills comprising, in combination, a drive shaft rotatably mounted in the still, a carriage slidably mounted on said shaft and rotatable therewith, cleaning elements on said carriage to contact with the wall of the still, means for alternately rotating said shaft first in one direction and then in the opposite direction, and means for moving the carriage longitudinally of the shaft in opposite directions.

in consonance with the rotation of the shaft in opposite directions, said shaft-rotating means including gears freely rotatable upon the shaft, means for rotating said gears in opposite directions, a clutch for coaction with each of said gears slidably mounted upon the shaft, means operating automatically to synchronously operate said clutches and alternately effect their coaction with the respective gears at the end of each longitudinal travel of the carriage, and means for retarding the engagement of the clutches with the respective gears. ¹⁰

In testimony whereof I affix my signature.

JAMES WILLIAM BOOTH. [L. S.]
